EXHAUST STEAM INJECTOR

Emanuel Rawson, North Bergen, and Joseph F. Griffin, Teaneck, N. J., assignors to The Superheater Company, New York, N. Y.

Application April 10, 1933, Serial No. 665,246

20 Claims. (Cl. 103—265)

The present invention relates to exhaust steam injectors and has particular reference to exhaust steam injectors of the multiple-stage type for delivering boiler feed water against relatively high boiler pressures. Still more particularly the invention relates to two-stage exhaust steam injectors of the type in which the low pressure stage is operated by exhaust steam from an engine when such steam is available and is operated by low pressure live steam when exhaust steam is not available, and in which the high pressure stage is operated by high pressure live steam at all times when the injector is in operation.

When injectors of the above general type are utilized to supply feed water to the boilers of locomotives, it is at times difficult, if not impossible, to keep the two stages of the injector in step, with the result that operation of the injector is interrupted due to "breaking" of the injector. This difficulty can be understood easily when it is realized that the first or low pressure stage is responsible for the supply of water to the second or high pressure stage. Because of this factor, unstable conditions of operation in the low pressure stage may cause the supply of water to the second stage to be interrupted, thus causing the high pressure stage to "break" with resulting interruption of delivery of water by the injector. Furthermore, when it is considered that the low pressure stage must work with exhaust steam, the pressure of which may fluctuate between wide limits, it will be appreciated that troublesome unstable conditions of operation of the low pressure stage may easily arise. Unstable operation of the low pressure stage is particularly likely to occur when change-over of operation of the injector from exhaust steam operation to live steam operation, or the reverse, takes place.

When change-over to exhaust steam operation occurs, exhaust steam is substituted for live steam in the low pressure stage. While this substitution may require a time of only a few seconds, the interval may be sufficient to cause momentary spilling at the over-flow of the low pressure stage which is reflected in an interrupted water supply or delivery to the high pressure stage. During this period of interruption, the high pressure stage lacks the water necessary to condense the high pressure live steam admitted thereto, and this stage, therefore, "breaks" and its action cannot be restored without first shutting off the entire injector and re-starting it. Furthermore, in re-starting the injector, or in fact when starting

the injector at any time, the operator must be careful not to admit operating steam to the high pressure stage until stable operating conditions have been established in the low pressure stage so as to provide a delivery of water to the high pressure stage. Otherwise, the high pressure stage will fail to function because of lack of water to condense the steam admitted to this stage.

The general object of the present invention is to provide means for eliminating the difficulties of the above-described character, and this general object is attained by the provision of means acting in response to an impulse indicative of stability of operation of the low pressure stage of the injector for controlling the admission of operating steam to the high pressure stage of the injector. The detailed nature of the invention, together with the more detailed objects thereof, and the manner in which these objects are attained may best be understood from the following description of forms of apparatus suitable for carrying the invention into effect, taken in conjunction with the accompanying drawings forming a part of this specification:

In the drawings, Fig. 1 is a more or less diagrammatic side elevation, partly in section, showing the application to a locomotive of an injector embodying the invention;

Fig. 2 is a section on enlarged scale of a valve shown in Fig. 1;

Fig. 3 is a section of part of an injector similar to that shown in Fig. 1 and adapted to actuate a form of valve somewhat different from that shown in Fig. 2;

Fig. 4 is a view partly in section of a valve similar to the valve shown in Fig. 2 but adapted to operate with an injector of the form shown in Fig. 3; and

Fig. 5 is an elevation partly in section showing still another form of injector and control valve arrangement.

Referring now to Fig. 1, the injector, indicated generally at A, is of known type and comprises a low pressure stage indicated generally at B and a high pressure stage indicated generally at C. Water is admitted to the low pressure stage from the supply pipe 10 controlled by the valve 12 manually operable by means of the control handle 14 located in the cab of the locomotive, which is indicated generally at D. Low pressure steam is admitted to the low pressure stage through the steam supply pipe 16 leading from the exhaust passage of the engine cylinder 18 and in communication with the low pressure steam

chamber 20 of the injector. Flow of low pressure steam from chamber 20 to the combining nozzle 22 is controlled by valve 24 manually operable from the cab by means of the control lever 26.

5 High pressure live steam for operating the injector is supplied from the turret of the locomotive boiler through the main supply pipe 28. Flow through pipe 28 is controlled by the main control valve 30 having an operating handle 32 10 suitably located in the cab.

10 A branch pipe 34 connects pipe 28 with valve 36 and valve 38 is automatically controlled under the influence of live steam pressure conducted to the valve from the steam chest of the engine cylinder through pipe 38. This control is arranged so that when live actuating steam is admitted to valve 36 through pipe 38 upon the admission of steam to the engine cylinder, valve 36 is closed. A valve 40 is provided for controlling flow of exhaust steam from the engine through conduit 16 and through a suitable connection indicated at 42 live steam from conduit 38 acts to open valve 40 when the engine is running and exhaust steam is available. Upon the failure of 20 a supply of actuating steam in pipe 38 due to closing of the engine throttle, valve 40 is closed and valve 36 is opened due to pressure of steam admitted through connection 34. When valve 36 is opened, live steam from the connection 34 flows 25 by way of connection 44 to the low pressure steam supply pipe 16, this steam being suitably throttled to reduce its pressure to a value substantially that of average exhaust steam pressure.

30 The part of the control system just described, which functions to admit exhaust steam to the supply pipe 16 when the engine is running and to admit low pressure live steam when the engine is not running, is known and need not be described in further detail herein. The novel features of the control system will be pointed out hereinafter in conjunction with the description of 35 operation of the apparatus.

35 Returning to the injector, combining tube 22 of the low pressure stage is in communication with the usual over-flow chamber 46 having a gravity loaded over-flow valve 48. The jet formed in the combining tube 22 flows through the delivery tube 50 of the low pressure stage to the low pressure delivery chamber 52, which is 40 in communication, by way of check valve 51, with the inlet end of the combining tube 54 of the high pressure stage. High pressure live steam for operating the high pressure stage is admitted 45 through pipe 28 and steam nozzle 56 to the combining tube 54, and the jet formed in this combining tube passes through the delivery tube 58 to the high pressure delivery chamber 60 from which water flows by way of the check valve 62 and delivery pipe 64 to the boiler of the locomotive. The combining tube 54 is in communication 50 with over-flow chamber 66 and flow of water from chamber 66 is controlled by the pressure loaded over-flow valve 68 which may advantageously be loaded by the pressure of water admitted 55 to a suitable actuating piston through the channel 70 to which water under pressure is admitted when the check valve 62 is lifted from its seat.

60 In the embodiment of the invention shown in Fig. 1, the present invention is carried into effect 65 by means of an automatic valve indicated generally at E for controlling flow of live steam through pipe 28 to the nozzle 56 of the high pressure stage of the injector. The actuating mechanism for this valve is responsive to delivery pressure from the low pressure stage of the injector

and this pressure is transmitted to the valve operating mechanism from the delivery chamber 52 through the connection 72. A vent pipe 74 connects the valve mechanism with the low pressure steam supply pipe 16.

5 Turning now to Fig. 2, valve E is shown in detail and comprises a valve body 76 having an inlet chamber 78 to which one portion of the high pressure steam pipe 28 is connected and an outlet chamber 80 to which another portion of the pipe 10 10 leading to the injector is connected. Flow of steam from chamber 78 to chamber 80 is controlled by the valve member 82, actuated by piston 84 suitably mounted in the valve body 76. The upper face of piston 84 is subject to the 15 pressure of live steam admitted to the inlet chamber 78 and chamber 78 is placed in restricted communication with chamber 86 below the piston by means of a small leak passage 88 passing through piston 84. Chambers 78 and 86 may be placed in restricted communication by other 20 suitable means such, for example, as a leak passage in the wall of the valve body 76 or by making piston 84 a relatively loose fit in the portion of the valve body in which it is mounted. Chamber 86 is provided with a vent port 90 controlled by a needle or pin valve 92 and the outlet of port 90 communicates with a vent chamber 94 which 25 may be in communication with any low pressure zone but which is preferably connected to the low 30 pressure steam supply pipe 16 by means of the vent pipe 74. The pin valve 92 is carried by a diaphragm 96 below which is the pressure chamber 98 with which the connection 72 communicates. A spring 100, the tension of which is 35 preferably made adjustable by means of a suitable adjusting screw 102, serves to keep the pin valve 92 open in the absence of pressure in chamber 98 acting on the diaphragm 96.

40 The operation of this embodiment of the apparatus is as follows:

45 Let it be assumed that the injector is to be started. The water valve 12 is opened to admit water to the low pressure stage of the injector and valve 24 is opened so as to admit low pressure steam from chamber 20. Let it also be assumed that the engine is not operating and exhaust steam is not available. The main control valve 30 is opened, and valve 36 being open, a supply of live steam at low pressure flows through 50 connections 34 and 44 to the low pressure supply pipe 16 and chamber 20.

55 Flow of high pressure steam past the automatic valve E is prevented; under the assumed conditions, because with the injector not in operation the pin valve 92 is open and chamber 86 is vented by way of the vent pipe 74. With chamber 86 vented, the pressure of live steam in the inlet chamber 78 and acting on the upper face of piston 84 over-balances the pressure acting on the under-side of the head of the valve member 82 and maintains this valve closed. Thus by opening valve 30 the proper supplies of water and low pressure steam necessary for starting the low pressure stage of the injector are made available at this stage while the supply of operating steam for the high pressure stage is cut off by the automatic valve E. Under these conditions ready starting of the low pressure stage of the injector is insured upon the opening of the steam valve 24 and the water valve 12, since there is no chance for interference with the starting of the low pressure stage due to flow to the delivery end of this stage of high pressure operating steam intended for operation of the high pressure stage. In this con- 60 65 70 75 80 85 90 95 98 100 105

nection it is to be noted that because of this arrangement a single manually operable starting valve 30, admitting all of the high pressure live steam needed by the injector to a single supply pipe 28, is all that is required in order to have a structure which insures against difficulty or impossibility of starting the low pressure stage of the injector due to the blow into this stage of high pressure steam intended for the actuation of the high pressure stage. After the admission of water and low pressure steam to the low pressure stage of the injector, this stage of the injector establishes a jet which results in delivery of water under pressure to chamber 52 and to the combining nozzle 54 of the high pressure stage. As soon as this is accomplished, the pressure from chamber 52, transmitted through the connection 72 to the chamber 98 of the automatic valve E, closes the pin valve 92. When valve 92 is closed, high pressure steam leaking through the passage 88 builds up pressure in chamber 86 to over-balance piston 84 and the valve member 82 is moved to open position to admit high pressure operating steam to the nozzle 56 of the high pressure stage. Since the admission of operating steam to the high pressure stage is delayed until after water is admitted to this stage due to the commencement of operation of the low pressure stage, the high pressure stage is enabled to establish a jet and to commence normal operation without difficulty.

Let it now be assumed with the injector operating that the locomotive engine is started and exhaust steam becomes available. The portion of the control system comprising valves 36 and 40 operates automatically to close the live steam admission valve 36 and open the exhaust valve 40, but during this change-over period there may be some interruption in the continuity in the supply of low pressure steam through pipe 16. If this interruption in the supply of operating steam to the low pressure stage is sufficient to cause the low pressure stage to commence spilling through the over-flow and to cease normal delivery of water to the high pressure stage, the failure of delivery pressure in chamber 52 will result in opening of the vent passage in the automatic valve E and consequent closing of this valve. This automatically prevents the continued supply of high pressure operating steam to the high pressure stage, which under the conditions assumed is not receiving its normal supply of water from the low pressure stage. As soon as the low pressure stage of the injector recommences operation on exhaust steam and water is supplied by this stage to the high pressure stage, the automatic valve E again permits high pressure operating steam to flow to the high pressure stage of the injector and normal operation of the injector recommences without manipulation of the control on the part of the operator. It will be evident that upon change-over of the injector back to live steam operation, in case the engine throttle is closed, the automatic valve E will function in the manner above described in case the change-over results in sufficient interruption in the continuity of the supply of low pressure steam to the injector to cause the low pressure stage thereof to spill and cease to deliver a normal supply of water to the high pressure stage.

In the hereinabove described embodiment of the invention, the factor indicative of stability of operation of the low pressure stage of the injector which is employed to provide the impulse for actuating or controlling the automatic valve controlling the supply of live steam to the high

pressure stage of the injector is the delivery pressure of the low pressure stage. It is well known that the pressure in the over-flow chamber of an injector is indicative of the stability of operation of the injector, and in the exercise of the present invention over-flow pressure rather than delivery pressure may be employed to control the action of the valve for controlling admission of live steam to the injector. 5

In the present state of development of multiple-stage exhaust steam injectors of the general type disclosed in Fig. 1, the low pressure stage of the injector does not deliver water heated to a temperature above the vaporizing temperature at atmospheric pressure and the pressure in the over-flow chamber under conditions of stable operation is less than atmospheric. In other words, when this stage of the injector is operating normally a partial vacuum exists in the over-flow chamber. It is for this reason that 10 the over-flow valve of the low pressure stage does not have to be a pressure loaded valve in order to prevent spilling at the over-flow when the injector is operating. 15

The application of the present invention to an injector of the type shown in Fig. 1, in a manner such that the impulse for controlling the automatic live steam control valve is derived from over-flow pressure, is illustrated in Figs. 3 and 4. In Fig. 3 a connection 72' is shown in 20 communication with the over-flow chamber 46 of the low pressure stage of the injector. Connection 72' connects this chamber with the actuating mechanism of an automatic valve E', the construction of which is shown in Fig. 4. 25

Referring now more particularly to Fig. 4, the upper portion of the valve, including the inlet and outlet chambers in the valve body and the movable valve member including its actuating piston 84, is the same as that already described in 30 connection with Fig. 2. In the present valve arrangement, however, the pressure chamber 98' with which the connection 72' communicates is above the diaphragm 96 which carries the pin valve 92 rather than below the diaphragm as in 35 the form of valve shown in Fig. 2. In the present embodiment, the spring 100 tends to hold the pin valve away from its seat so as to vent chamber 86 and maintain the valve controlling flow 40 through pipe 28 closed and this condition will 45 obtain whenever the low pressure stage of the injector is not operating with sufficient stability to produce the sub-atmospheric pressure in the over-flow chamber of this stage of the injector which occurs during normal operation thereof. 50 If the low pressure stage of the injector is in normal operation and is delivering water to the high pressure stage of the injector, a partial vacuum will exist in the over-flow chamber of the low pressure stage, and this partial vacuum, 55 transmitted to chamber 98' through the connection 72', will operate to close the pin valve 92 and effect opening of the valve controlling flow through pipe 28, in the manner already described. 60

From the above it will be evident that the action of the valve E' in the present embodiment in preventing breaking of the injector upon change-over of operation, or at any other time when the low pressure stage is not operating normally, is 65 the same as that described in connection with Figs. 1 and 2. 70

In case an injector of the multiple-stage type is designed so that the low pressure stage delivers water heated to a temperature above the 75

vaporizing temperature at atmospheric pressure, the low pressure stage may under certain conditions of operation operate with a pressure in the over-flow chamber which is greater than atmospheric. In such an arrangement the over-flow valve of the low pressure stage should be loaded when the injector is in operation in order to permit an over-flow chamber pressure in excess of atmospheric to be built up. In Fig. 5 there is shown an arrangement suitable for carrying the present invention into effect with the automatic steam control valve actuated in response to the over-flow chamber pressure of a low pressure stage in which this pressure during normal operation may exceed atmospheric.

Referring now more particularly to Fig. 5, the injector is indicated generally at A and the over-flow valve for the low pressure stage of the injector is indicated at 48. At the side of the injector body there is provided a cylinder 104 forming a pressure chamber 106 in communication with the delivery chamber 52 of the low pressure stage of the injector. Slidably mounted within the cylinder 104 and in communication at its end with chamber 106 is the plunger 108 having an aperture at its upper end. A lever 110 pivoted to the injector body at 112 is provided with an arm 114 adapted to contact a stem 116 of valve 48 and an arm 118 on the opposite side of the pivot and passing through the aperture in the upper end of the plunger 108. The automatic valve E' is mounted adjacent to the cylinder 104 and the upper portion of the valve body and the valve member including piston 84 are the same as in the valve forms previously described. In the present embodiment the pin valve 92 is provided with a slot 120 through which projects the outer end of arm 118 and also a flat spring 122 attached to the upper face of this arm. When plunger 108 is raised due to pressure in chamber 106, the pin valve 92 is resiliently seated by spring 122, this spring being included in the motion transmitting mechanism so as to insure proper seating of both valves 48 and 92 due to movement of the common operating lever 110. Preferably, a coil spring 124 is placed below the outer end of the lever arm 114, this spring tending to move the parts to the position shown in Fig. 5 so that in the absence of pressure in chamber 106 the over-flow valve 48 will be free to open. The principal function of spring 124 is to overcome any resistance to movement of the plunger 108 that may be occasioned by the packing around this plunger, which resistance in the absence of the spring, might impose a load on valve 48 when this valve should be entirely unloaded.

As will be observed from the drawings, the valve E' is shown in Fig. 5 as turned 180° from the position in which valves E and E' are shown in Figs. 2 and 4 respectively, but it will be evident that the connection of the valve E' in the live steam supply pipe 28 is in effect the same as in the embodiments previously described.

In the present embodiment the apparatus functions as follows:

When the injector is not in operation, the spring 124 holds the lever 110 in the position shown in Fig. 5 and the overflow valve at the low pressure stage is free to open. When the injector is started and steam and water are admitted to the low pressure stage, over-flow through valve 48 occurs until the jet is established, when over-flow ceases. During this time

sure stage is built up, the pin valve 92 is open and valve E' acts to prevent operating steam from reaching the high pressure stage of the injector. When the low pressure stage goes to work and delivery pressure is built up in chamber 52, it acts on plunger 108 to effect closure of the pin valve 92 and at the same time to impose closing pressure on the over-flow valve 48 through the medium of the lever arm 114. When the pin valve 92 is closed, valve E' is opened to admit operating steam to the high pressure stage in the manner previously described. If and when stable operation of the low pressure stage is interrupted, delivery pressure on plunger 108 fails and under the influence of spring 124 the parts assume the position shown in the figure, effecting closure of valve E' and permitting the low pressure stage to spill through the over-flow valve 48 so as to enable the low pressure stage to re-start.

It is evident that in the above described embodiment the delivery pressure of the low pressure stage is the factor providing the actuating impulse controlling the steam supply valve for the high pressure stage, as in the embodiment illustrated in Fig. 1, but in the present embodiment the delivery pressure is also employed to enable continued operation of the low pressure stage of the injector even when the over-flow chamber pressure in this stage is greater than atmospheric. It will further be evident that with an injector adapted to operate with an over-flow pressure greater than atmospheric in the low pressure stage, control of the valve governing the supply of operating steam to the high pressure stage may be effected in response to over-flow pressure of the low pressure stage by means of valve operating mechanism of the form shown in Fig. 2.

It is to be understood that unless such interpretation is inconsistent with the use of the term "pressure" as herein employed shall refer to absolute pressure and shall include sub-atmospheric pressures as well as pressures above atmospheric.

From the foregoing description of the several embodiments herein illustrated, it will be appreciated that the invention can be carried into effect with numerous different forms and arrangements of apparatus, and the invention is accordingly to be understood as not confined in its scope to the illustrative embodiments herein disclosed but is to be considered as embracing all forms and arrangements of the apparatus falling within the scope of the appended claims when construed as broadly as the state of the prior art permits.

We claim:

1. Apparatus of the character described comprising a multiple-stage injector having stages serially connected with respect to flow of water through the injector and comprising a low pressure stage adapted to be operated by low pressure steam and a stage of relatively higher pressure adapted to be operated by steam of higher pressure than said low pressure steam, and valve means automatically operable under the influence of a factor indicative of the condition of operation of the low pressure stage of the injector to admit operating steam to said stage of relatively higher pressure when the low pressure stage is delivering a normal quantity of water and to prevent admission of operating steam to said stage of relatively higher pressure when the low pressure stage is not delivering a normal quantity of water.
2. Apparatus of the character described comprising a multiple-stage injector having stages

serially connected with respect to flow of water through the injector and comprising a low pressure stage adapted to be operated by low pressure steam and a stage of relatively higher pressure adapted to be operated by steam of higher pressure than said low pressure steam, and valve means automatically operable in response to a pressure impulse indicative of stability of operation of the low pressure stage for admitting operating steam to said stage of relatively higher pressure when the low pressure stage is delivering a normal quantity of water and for preventing admission of operating steam to said stage of relatively higher pressure when the low pressure stage is not delivering a normal quantity of water.

3. Apparatus of the character described comprising a multiple stage injector having stages serially connected with respect to flow of water through the injector and comprising a low pressure stage adapted to be operated by low pressure steam and a stage of relatively higher pressure adapted to be operated by steam of higher pressure than said low pressure steam, and valve means automatically operable in response to a fluid pressure impulse indicative of stability of operation of the low pressure stage for admitting operating steam to said stage of relatively higher pressure when the low pressure stage is delivering a normal quantity of water and for preventing admission of operative steam to said stage of relatively higher pressure when the low pressure stage is not delivering a normal quantity of water.

4. Apparatus of the character described comprising a multiple-stage injector having stages serially connected with respect to flow of water through the injector and comprising a low pressure stage adapted to be operated by low pressure steam and a stage of relatively higher pressure adapted to be operated by steam of higher pressure than said low pressure steam, conduits for supplying operating steam separately to said stages, a valve for controlling flow of steam through the conduit supplying the stage of higher pressure, and actuating means for said valve operable in response to an impulse indicative of stability of operation of the low pressure stage for preventing flow of operating steam to the stage of higher pressure when the low pressure stage is not in a condition of stable operation.

5. Apparatus of the character described comprising a multiple-stage injector having stages serially connected with respect to flow of water through the injector and comprising a low pressure stage adapted to be operated by low pressure steam and a stage of relatively higher pressure adapted to be operated by steam of higher pressure than said low pressure steam, conduits for supplying operating steam separately to said stages, a valve for controlling flow of steam through the conduit supplying the stage of higher pressure, and actuating means responsive to delivery pressure of the low pressure stage for automatically opening said valve when the low pressure stage is in normal operation.

6. Apparatus of the character described comprising a multiple-stage injector having stages serially connected with respect to flow of water through the injector and comprising a low pressure stage adapted to be operated by low pressure steam and a stage of relatively higher pressure adapted to be operated by steam of higher pressure than said low pressure steam, conduits for supplying operating steam separately to said stages, a valve for controlling flow of steam through the conduit supplying the stage of higher pressure, and actuating means responsive

to over-flow pressure of the low pressure stage for automatically opening said valve when the low pressure stage is in normal operation.

7. In injector apparatus having a pressure stage to which water is delivered from a second stage of lower pressure, a valve for controlling the admission of operating steam to the first mentioned stage, and valve control means operable under the influence of a factor indicative of the condition of operation of the low pressure stage of the injector for causing said valve to open when the second mentioned stage is in normal operation.

8. In injector apparatus having a pressure stage to which water is delivered from a second stage of lower pressure, a valve for controlling the admission of operating steam to the first mentioned stage, and operating mechanism associated with said valve and operable under the influence of a factor indicative of the condition of operation of the low pressure stage of the injector to cause said valve to permit operating steam to be admitted to the first mentioned stage when the second mentioned stage is in normal operation and to prevent the admission of operating steam to the first mentioned stage when the second mentioned stage is not in normal operation.

9. Apparatus of the character described comprising a multiple-stage injector having a low pressure stage adapted to be operated by exhaust steam and a high pressure stage adapted to be operated by live steam, conduits for supplying exhaust steam and live steam to said stages respectively, a valve for controlling flow of steam through the live steam conduit, and means responsive to an impulse indicative of stability of operation of the low pressure stage of the injector for opening said valve when the last mentioned stage is not in stable operation.

10. Apparatus of the character described comprising a multiple-stage injector having a low pressure stage adapted to be operated by exhaust steam and a high pressure stage adapted to be operated by live steam, conduits for supplying exhaust steam and live steam to said stages respectively, a valve for controlling flow of steam through the live steam conduit, and pressure responsive means for automatically opening said valve in response to establishment by the low pressure stage of a pressure indicative of stable operation of said low pressure stage.

11. The combination, with a multiple stage injector having an automatic control system including conduits for supplying exhaust steam or low pressure live steam to the low pressure stage of the injector and high pressure live steam to the high pressure stage of the injector, of a valve located in the high pressure live steam supply conduit and actuating means for said valve comprising pressure responsive parts acting under the influence of an impulse indicative of stability of operation of the low pressure stage of the injector for automatically admitting operating steam to the high pressure stage only when the low pressure stage is delivering a sufficient quantity of water to the high pressure stage to insure proper operation thereof.

12. In injector apparatus having a pressure stage to which water is delivered from a second stage of lower pressure, a conduit for admitting operating steam to the first mentioned stage, a valve for controlling flow of steam through said conduit, said valve being adapted to be closed by pressure of steam admitted to the conduit, and

pressure responsive means responsive to the establishment by the second mentioned stage of a pressure indicative of normal operation thereof for automatically opening said valve.

5 13. In injector apparatus having a pressure stage to which water is delivered from a second stage of lower pressure, a conduit for admitting operating steam to the first mentioned stage, a valve controlling flow of steam through said conduit, said valve adapted to be closed by pressure of steam admitted to the conduit, steam pressure actuated means comprising a vent valve for causing the first mentioned valve to open and pressure responsive means responsive to delivery pressure from the second mentioned stage for actuating said vent valve.

10 14. In injector apparatus having a pressure stage to which water is delivered from a second stage of lower pressure, a conduit for admitting operating steam to the first mentioned stage, a valve controlling flow of steam through said conduit, said valve adapted to be closed by pressure of steam admitted to the conduit, steam pressure actuated means comprising a vent valve for causing the first mentioned valve to open and pressure responsive means responsive to over-flow pressure from the second mentioned stage for actuating said vent valve.

15 15. In injector apparatus, a high pressure stage, a low pressure stage for delivering water to the high pressure stage, said low pressure stage having an over-flow valve, means responsive to delivery pressure of the low pressure stage for loading said over-flow valve and means associated with said first mentioned means for automatically admitting operating steam to the high pressure stage when the first mentioned means is actuated by delivery pressure to load said over-flow valve and for preventing admission of operating steam to the high pressure stage in the absence of delivery pressure from the low pressure stage.

20 16. Apparatus of the character described comprising a multiple stage injector having stages serially connected with respect to flow of water through the injector and comprising a low pressure stage adapted to be operated by low pressure steam and a stage of relatively higher pressure adapted to be operated by steam of higher pressure than said low pressure steam, a conduit for supplying said steam of higher pressure to the last mentioned stage, a valve for controlling flow of steam through said conduit, and pressure responsive means for opening said valve in response to delivery of water at predetermined pressure by said low pressure stage to the stage of higher pressure.

25 17. Apparatus of the character described comprising a multiple stage injector having stages serially connected with respect to flow of water through the injector and comprising a low pressure stage adapted to be operated by low pressure steam and a stage of relatively higher pressure adapted to be operated by steam of higher pressure than said low pressure steam, a conduit for supplying said steam of higher pressure to the last mentioned stage, a valve in said conduit for controlling flow of steam therethrough, means

30 associated with the valve for closing the same, and pressure responsive means automatically operable in response to delivery of water at predetermined pressure from the low pressure stage to the stage of higher pressure for opening said valve.

35 18. Apparatus of the character described comprising a multiple stage injector having stages serially connected with respect to flow of water through the injector and comprising a low pressure stage adapted to be operated by low pressure steam and a stage of relatively higher pressure adapted to be operated by steam of higher pressure than said low pressure steam, a conduit for supplying said steam of higher pressure to the last mentioned stage, and an automatic valve in said conduit for admitting operating steam to said stage of relatively higher pressure when the low pressure stage is supplying water thereto and for shutting off operating steam from said stage of relatively higher pressure when the low pressure stage is not supplying water thereto.

40 19. Apparatus of the character described comprising a multiple stage injector having a low pressure stage adapted to be operated in alternation by low pressure live steam or exhaust steam from an engine and a high pressure stage adapted to be operated by high pressure live steam and receiving water delivered from said low pressure stage, a low pressure steam conduit for delivering low pressure operating steam to said low pressure stage, a high pressure conduit for delivering high pressure steam to said high pressure stage, a manually operable control valve in said high pressure conduit, an automatic valve in said high pressure conduit between the manually operable valve and said high pressure stage, means for causing said automatic valve to remain closed when said low pressure stage is not delivering water to the high pressure stage, and means for causing said automatic valve to open when the low pressure stage is delivering water to the high pressure stage.

45 20. Apparatus of the character described comprising a multiple stage injector having a low pressure stage adapted to be operated in alternation by low pressure live steam or exhaust steam from an engine and a high pressure stage adapted to be operated by high pressure live steam and receiving water delivered from said low pressure stage, a low pressure steam conduit for delivering low pressure operating steam to said low pressure stage, a high pressure conduit for delivering high pressure steam to said high pressure stage, a manually operable control valve in said high pressure conduit, an automatic valve located in said high pressure conduit between said manually operable valve and said high pressure stage, said automatic valve operating to shut off the steam supply to said high pressure stage when the low pressure stage is not delivering water to the high pressure stage, and a connection for supplying steam to said low pressure conduit from said high pressure conduit, said connection communicating with the portion of said high pressure conduit between said valves.
